United States Patent Office.

HENRY KEWLEY, OF PERRY, OHIO.

Letters Patent No. 71,764, dated December 3, 1867.

IMPROVEMENT IN HAY-RAKERS AND LOADERS.

The Schedule referred to in these Letters Patent and making part of the same.

TO ALL WHOM IT MAY CONCERN:

Be it known that I, HENRY KEWLEY, of Perry, in the county of Lake, and State of Ohio, have invented an improved Machine for Raking and Loading Hay; and I do hereby declare that the following is a full and exact description of the same, reference being had to the accompanying drawings, making part of this specification, and which are numbered respectively 1, 2, 3, and 4—

No. 1 being a side elevation of the machine.

No. 2, a detached portion of the rear end thereof, representing principally, the inside of the improved raking-device employed.

No. 3, a view of the outside of the same; and

No. 4, an end elevation of the upper part of the said machine, showing the improved apron-arrangement employed.

The letters of reference marked thereon indicating the same parts in all the drawings.

My invention consists, first, of a raking-device constructed with teeth that move or slide up and down in a suitable frame by their own gravity, and independent of each other, in such manner as, when passing over the ground, each tooth will rise and fall with any unevenness, thereby insuring the raking of the whole surface; second, in providing an apron or broad chute (constructed as will be explained) at the top of the machine, for more effectually guiding and delivering the hay, and without spilling, to be loaded.

The following will enable others skilled in the art to understand and construct the same.

A, fig. 1, is an axle-tree or shaft, mounted on a pair of driving-wheels, B. On said shaft is built a polygonal reel, C. D is another shaft provided with a similar reel, E. This latter shaft and reel are supported, in the elevated position shown in the figure, by two long side rails, F, the lower ends of which rest on the axles of the lower shaft A. The said rails are held together by ties G G and cross-braces H H, and are further strengthened by the brace-rod H', attached to the frame hereinafter mentioned. I is a pair of jointed or linked bands, the joints or links being of a length corresponding to the sides of the said polygonal reels. Across said bands is secured, at intervals, a sufficient number of conveyers, J, each carrying four or more tines K, and are so arranged on the conveyers as to pass clear of the teeth of the raking-device, hereafter mentioned, and the fingers of the pivoted apron, hereafter described. Supported on the axles of shaft A, by arched standards L, are two sides, L', of a framework, which unite at the forward end, forming a tongue, M. The rear ends of said sides L' are each bent or turned, forming return parts N. These return parts support a frame, N', the construction of which is seen in fig. 2. Pivoted on the extreme ends of said return parts is the raking-device (before referred to) as shown at N², fig. 2. This said raking-device is constructed thus: Two side pieces, O, are secured to a head, P. The lower ends of said side pieces are mortised into a rail, Q, on the ends of which are journals, R. The upper and lower portions of said head, P, are provided with a series of holes, through which the set or series of long rake-teeth S is passed, and is prevented from slipping entirely out by pins T. Thus the said rake-teeth have a slide movement equal to the height of the head P. The frame or head of the said raking-device, it will be seen on reference to figs. 1 and 2, is held in position so as to allow the teeth to stand at an angle of forty-five degrees, or thereabout. The arm T², which is supported on a short standard, T¹, on the said frame N', will hold it in the required position by the pendent rods T³ and T⁴. Near the top of each of the long side rails F, fig. 1, are secured supports U. To these is pivoted an apron or broad chute, U¹, (before referred to.) Said apron is provided with deep turned-up sides U², and a series of fingers U³, on its upper portion, as represented in fig. 4. Said apron is suspended in proper position by cords W W.

The operation is as follows: The machine is attached to the rear under part of the hay-wagon by the tongue M, and is drawn over the field in any direction the scattered hay may happen to lie, without reference to wind-rows. As fast as the hay accumulates forward of the rake, it is taken up by the fingers of the conveyers to the top of the machine, when it drops on the apron, which holds it, without falling or spilling from the sides, until removed to the load by the attendant.

It will be seen that my arrangement of employing a series of independent and self-adjusting rake-teeth must necessarily result in raking the field clean, as all the hollows or depressions of the ground are effectually reached.

What I claim as my invention, and desire to secure by Letters Patent, is—

1. The raking-device herein described, consisting of the series of movable and independent rake-teeth S, rake-head P, provided with apertures, side pieces O O, rail Q, journals R R, stop-pins T, arm T², and pendent rods T³ T⁴, all arranged and operating as and for the purpose herein specified.
2. The said raking-device, constructed as herein described, in combination with the conveyers J, provided with sets of lines K and bands I, as and for the purpose set forth.
3. The pivoted apron or broad chute U¹, constructed with a series of fingers, U³, and turned-up sides U², supports U, and cords W, arranged and operating as and for the purpose specified.

HENRY KEWLEY.
